(57) CLAIM

The ornamental design for a display case for autographed/collectible scripts, as shown and described.

DESCRIPTION

FIG. 1: is a perspective view of a display case; with a cover attached to the base of the display case showing my new design;

FIG. 2: is an exploded left side elevational view, the right-side exploded elevational view being a mirror image thereof;

FIG. 3: is an exploded front elevational view thereof;

FIG. 4: is an exploded rear elevational view thereof;

FIG. 5: is a top plan view thereof;

FIG. 6: is a bottom plan view thereof; and,

FIG. 7: is a top plan view with the cover attached to the base of the display case.

1 Claim, 4 Drawing Sheets
